UNITED STATES PATENT OFFICE.

JAMES H. BUNTING, OF CLIFTON, NEW JERSEY, ASSIGNOR TO SUSQUEHANNA SILK MILLS, A CORPORATION OF NEW YORK.

DESIGN FOR A TEXTILE FABRIC.

Application filed September 27, 1924. Serial No. 10,916. Term of patent 3½ years.

To all whom it may concern:

Be it known that I, JAMES H. BUNTING, a citizen of the United States of America, and resident of the town of Clifton, county of Passaic, and State of New Jersey, have invented a new, original, and ornamental Design for a Textile Fabric, of which the following is a specification, reference being had to the accompanying drawing, forming part thereof.

The figure is a plan view of a textile fabric, illustrating my new and ornamental design. That portion of the lower part of the fabric shown on the drawing is repeated throughout the length of the fabric.

I claim:

The ornamental design for a textile fabric as shown.

JAMES H. BUNTING.
